CLAIM

The ornamental design for a wheel cleaner for automotive vehicles, as shown and described.

DESCRIPTION

FIG. 1 is a right elevational view showing the design of my wheel cleaner for automotive vehicles, the left elevational view thereof being a mirror image of FIG. 1;
FIG. 2 is a top planar view thereof;
FIG. 3 is a rear elevational view thereof;
FIG. 4 is a frontal elevational view thereof; and,
FIG. 5 is a bottom planar view thereof.
